UNITED STATES PATENT OFFICE.

JOHN J. HENNESSEY, OF MILWAUKEE, WISCONSIN.

CENTER-BEARING FOR CARS.

1,009,306.

Specification of Letters Patent. Patented Nov. 21, 1911.

Application filed May 18, 1911. Serial No. 628,098.

To all whom it may concern:

Be it known that I, JOHN J. HENNESSEY, a citizen of the United States, residing in Milwaukee, in the county of Milwaukee and 5 State of Wisconsin, have invented a new and useful Improvement in Center-Bearings for Cars, of which the following is a specification.

It is well known that railroad cars sometimes become depressed in use below the limits prescribed by the United States safety 10 appliance standards and when this occurs it has been customary to insert in the circular recess of the truck center plate in which the 15 boss of the body center plate seats itself, a washer or other filling material adapted to raise and maintain the body center plate above the lower limit prescribed by said standards. This filling material creates a 20 liability on the part of the boss on the body plate to jump or ride out of the recess in the truck center plate and thereby to strain or break the center pin.

My object in this invention is to provide a 25 construction that will permit the car being raised above the truck to any desired height sufficient to support it within the limits required by law, and which will also prevent any tendency by the body plate to escape 30 from its recess in the truck plate and thus endanger the center pin. I accomplish these ends by employing an intermediate filling plate of the necessary vertical dimensions, such intermediate filling plate having upper 35 and lower faces which conform to and fit the opposing faces of the body and truck center plates. The details of this intermediate filling plate are fully explained below and also shown in the accompanying 40 drawing, in which latter—

Figure 1 is a vertical section of the invention showing the filling plate positioned between the body and truck center plates. Fig. 2 is a vertical section of the center plates 45 and the filling plate, showing them detached and ready to be assembled. Figs. 3 and 4 are views of the top and bottom faces of the filling plate. Fig. 5 is a vertical section of a modified construction. Figs. 6 and 7 are 50 face views of the top and bottom of the modified construction of the filling plate.

In said drawing 8 represents the body bolster of the car, and 9 is the body center plate secured to such bolster.

55 10 is the truck bolster, supporting the

truck center plate 11, and 12 is the usual center pin.

Between the two center plates is my newly invented intermediate filling plate 13. As shown, it may be of any thickness desired, 60 so long as its top and bottom faces conform to the opposing faces of the body and truck center plates, the intermediate plate acting equally well when thick as when thin, and if desired a plurality of them may be employed 65 by piling them one on top of another. By the conformity mentioned it will be understood that while the body plate has a central boss 14 surrounding the center pin, and outside of said boss a surrounding groove 15, 70 the top of the intermediate filling plate has a centrally located recess 14^a adapted to serve as a seat for the boss 14 and a surrounding ridge 15^a adapted to enter and fill the groove 15 of the body plate. Also that 75 while the bottom of the intermediate plate has a centrally depending boss 16^a and a surrounding groove 17^a such boss and groove corresponding in dimensions and all other respects to the boss 14 and groove 15 of the 80 body plate, the top surface of the truck plate has a central recess 16 in which the boss 16^a seats itself, and a ridge or raised rim 17 surrounding the boss 16^a adapted to enter and fill the groove 17^a. In other words, the intermediate filling plate embodies counterpart 85 faces of the opposing and contacting faces of both the body and truck center plates, so that when assembled with the intermediate filling plate between them the body plate 90 will be raised to the necessary extent and at the same time will be confined as securely in the truck plate as before the intermediate filling plate was inserted.

In the modifications shown in Figs. 5, 6 95 and 7, the body center plate 18 is made convex and the truck center plate 19 is concave and the boss 20 corresponding in function to the boss 14 of the other construction, is applied to the upper face of the intermediate 100 filling plate 21 and enters the recess 22 in the bottom of plate 18. The intermediate filling plate in this modified construction is dish shaped on one side and convex on the other, and in the bottom is a recess 24 adapted to receive a second boss 23 on the top of plate 19. Plate 21 is thus, it will be seen, the exact counterpart of the contacting faces of both center plates and serves the same 105 function as in the other construction.

It will be obvious that the body and truck center plates shown may be inverted, the body plate then becoming the truck plate, and the truck plate becoming the body plate, without changing their construction or their function, and that the filling plates shown may also be used without change other than inverting them with the inverted center plates.

10 I claim:—

1. The combination of a car truck and a car body, each provided with a center bearing plate, said bearing plates having faces provided with annular ridge and groove portions adapted to fit each other, and a removable plate adapted to be interposed between the center bearing plates, said removable plate having the face on one side thereof provided with annular ridge and groove portions similar to those on the truck center plate and having on its opposite side annular ridge and groove portions similar to those on the car body center plate, substantially as specified.
- 25 2. The combination in a center bearing for railway cars, of a body center plate, a truck center plate, and an intermediate filling plate interposed between said body and

truck center plates and having a boss surrounding the center pin upon one of its 30 faces, and adapted to seat itself in the recess of the opposing center plate, and also having a recess on its other face adapted to receive the boss of the other center plate.

3. The combination of a car body and a 35 car truck, each provided with a center bearing plate, one of said bearing plates having a centrally disposed boss adapted to fit a corresponding recess in the other bearing plate, and a removable filling plate interposed between the two bearing plates and having a centrally disposed boss similar to the first named boss and on the face farthest away therefrom and adapted to fit the first named recess, said filling plate having on its 40 opposite face a recess similar to the first named recess and adapted to fit the boss on the bearing plate whereby relative transverse movement of either bearing plate and the filling plate, and undue strain on the 45 center pin is prevented, substantially as specified.

JOHN J. HENNESSEY.
